UNITED STATES PATENT OFFICE.

GEORGE H. NEAL, OF FALLS CITY, NEBRASKA.

CRADLE.

SPECIFICATION forming part of Letters Patent No. 325,960, dated September 8, 1885.

Application filed June 16, 1885. (No model.)

To all whom it may concern:

Be it known that I, GEORGE H. NEAL, of Falls City, in the county of Richardson, in the State of Nebraska, have invented a new and useful Improvement upon Cradles for Babies, of which the following specification is sufficient in law.

My invention is a folding cradle—that is, a cradle having its several parts hinged together, in order that the article may be folded flat for economy of space in transportation.

In the drawings, Figure 1 represents the cradle set up for use; Fig. 2, half-folded; Fig. 3, folded.

15 A A² represent the end boards, B B² the side rails, and C C² the bottom rails, of the cradle. The posts of the end boards are supported by rockers D.

20 The foot rails are hinged in the center at a. The side rails are joined in the center by tongue and groove b c, and to the end boards by dovetail joints d e. The upright posts m, at the end of the cradle, are hinged to the bottom rails at o. All parts fold inwardly.

When the cradle is set up, the side rails are 25 secured to each other in the center by hooks and staples s, and their outer ends are secured to the upright posts by means of sliding bolts w.

The folding or setting up of the cradle is but half a minute's work. When folded, it is 30 so compact that its owner can conveniently transport it on a journey as part of the family's luggage.

I claim—

A baby's cradle constructed with its sides 35 and ends hinged to its bottom portion, the bottom hinged centrally, the sides united to each other in the center by tongue-and-groove joints and to the ends by dovetail joints, and properly secured, the cradle being adapted to 40 fold together in a flat condition, substantially as described.

In testimony whereof I affix my signature in presence of two witnesses.

GEORGE H. NEAL
